THERMAL TIME LAG FUSE

Gust A. Berthel, Chicago, Ill., assignor to Jefferson Electric Company, Bellwood, Ill., a corporation of Illinois

Application May 8, 1948, Serial No. 25,831

18 Claims. (Cl. 200—123)

1

This invention relates to an improved thermal time lag fuse in which the circuit breaking action may be provided by thermal responsive means other than the usual fuse link, and the invention relates also to a fuse link which is especially adapted for use in a cartridge fuse.

It is an object of my invention to provide a fuse link having thermal time lag means integrally incorporated therewith.

Fuses especially of the cartridge type, are frequently provided with means which serve to delay opening of the fusible element or link under low or moderate overload conditions. This type of fuse is oftentimes referred to as a time lag fuse. By the term "thermal time lag fuse," I refer to a time lag fuse which includes a body of fusible material which serves as a connecting link between two elements, at least one of which is stressed. The arrangement of parts is such that as the body of fusible material becomes softened, due to the increased temperature developed by small or moderate overload conditions, the stressed part is released, thus serving to open the circuit through the fuse.

A further object of my invention is to provide a thermal time lag fuse which is extremely simple in construction, and economical to manufacture, and which occupies substantially no more room than an ordinary fuse. Thus the fuse embodying my invention can be used in the usual type of cartridge fuse.

Another object of my invention is to provide a thermal time lag fuse construction having a resilient member in the form of a leaf spring. The leaf spring not only requires less space than a coil spring, but since it has a larger cross section, it can be used as one of the current carrying parts. This feature contributes to space and economy which is an important commercial feature, for the reason that the dimensions of the cartridge fuse are fixed by trade standards. Furthermore, this type of construction can be adapted for use in fuses of widely varying sizes.

Still another object of my invention is to provide a cartridge fuse construction which embodies a novel arrangement of lagging elements and a body of fusible metal, and in which the arrangement is such that considerable latitude in design is provided in order to obtain the blowing characteristics desired.

Still another object of my invention is to provide a fuse the maximum operating temperature of which is less than 300 degrees F.; thus, cooler operation and a lower watt loss is provided.

A further object of my invention is to provide

2

in a thermal time lag fuse construction, a resilient member which can be manufactured by a punching process, thereby providing enhanced uniformity of mechanical and electrical characteristics at low unit cost.

Other objects, features and advantages will become apparent as the description proceeds.

With reference now to the drawings, in which like reference numerals designate like parts,

10 Fig. 1 is an elevation, partly broken away, of one embodiment of my invention;

Fig. 2 is an end view of the embodiment shown in Fig. 1;

15 Fig. 3 is a plan view of just the fuse link portion of the fuse shown in Fig. 1;

Fig. 4 is an end view of the fuse link portion shown in Fig. 3;

15 Fig. 5 is an elevation of the fuse link portion of Fig. 3, but showing the parts in a changed position;

Fig. 6 is a section taken along line 6—6 of Fig. 5;

Fig. 7 is an elevation, partially broken away of another embodiment of my invention;

Fig. 8 is an end view thereof;

25 Fig. 9 is a plan view of the fuse link portion of the Fig. 7 device;

Fig. 10 is an end view of the fuse link portion shown in Fig. 9;

30 Fig. 11 is an elevation of the fuse link portion shown in Fig. 9 but with the parts in changed position;

Fig. 12 is an enlarged sectional view taken along line 12—12 of Fig. 9;

Fig. 13 is a plan view, similar to Fig. 3, showing 35 a modified form of fuse link; and

Fig. 14 is an elevation of the fuse link shown in Fig. 13.

With reference now to the embodiment shown in Figs. 1 to 6, inclusive, the reference numeral 40 20 designates generally a ferrule type fuse, for example, one having a sixty ampere rating. The fuse constitutes a casing 21 having slotted end caps 22 and 23 which may be suitably crimped on the casing 21, as by the dents 40. Within the casing are two copper strips 24 and 25, one at each end, and these are supported at their outer ends by the slotted end caps 22, 23, and at their intermediate portions by barriers 26 and 27, these barriers being in the form of disks which are stamped from a suitable insulating material, such as vulcanized fiber, of which material the casing 21 is also made.

The outer ends of the copper strips 24, 25 extend through the slots in the end caps 22, 23 and are electrically connected therewith by sol-

der 28. The barriers 26, 27 are also slotted, so as to receive not only the copper strips but also a bridge 29, also formed of suitable insulating material. The bridge 29 and the barriers form a rigid structure. Lagging strips 30 and 31, preferably of copper, are secured to the under side of the bridge 29, an eyelet 32 being used for this purpose with respect to the lagging strip 30 and a rivet 33 being used with respect to the lagging strip 31.

Each of the copper strips 24, 25 has a notched or drop-out quick blowing portion 34 and an inner portion 35 which rests on the bridge 29. The inner portion is provided with turned down side edges or wings 36 which overlap and contact the sides of the lagging strips 30, 31 in heat conducting relationship.

A leaf spring 37 formed of suitable spring material which is not affected by elevated temperatures is anchored at one of its ends by means of the rivet 33, the rivet holding the spring against copper strip 35 in a manner so as to provide an electrical contact. The spring 37 is preferably made of beryllium copper. The opposite or free end of the spring is provided with a bent down end 38, and the spring is, in its normal condition, stressed so that the end 38 is received within the eyelet 32 and is maintained in its stressed position by a body of solder 39. The solder preferably has a melting point of approximately 280° F.

The end portions of the interior of the casing 21 are filled with fuse powder 41, the barriers 26 and 27 serving to confine the fuse powder to said end portions, thereby leaving the central portion of the interior of the casing 21 unobstructed to permit free operation of the spring 37.

In operation, the parts are so designed that under short circuit conditions, the fuse will blow at the drop-out portions 34 of either one of the copper strips 24 or 25. However, under a low overload condition, the current passing through these copper strips 24 and 25, and also through the spring 37 generates a certain amount of heat which will gradually raise the temperature of the body of solder 39 to its softening or melting point. Thus, if the overloaded condition is continued, the solder 39 will become so soft that it is no longer sufficient to retain the spring 37 in its stressed position, with the result that the spring will be released and occupy the position shown in Fig. 5. Since the spring is the only metallic connection between the two halves of the fuse, the opening of the spring will cause the circuit to be opened. The eyelet construction permits the melted solder to run out of the eyelet, irrespective of the angular position of the fuse with the result that only a comparatively small portion of the solder is volatilized.

The lagging strips 30 and 31 serve to absorb the heat that is generated in the copper strips 24 and 25, and in the spring 37, and thus, they may be dimensioned so as to control the blowing of the fuse.

In Figs. 7 to 12, inclusive, a blade type cartridge fuse, designated generally by the reference numeral 44, is shown. This fuse comprises a casing 45 having slotted end caps 46 and 47, through which extend blades 48 and 49. A bridge 50 within the casing provides physical connection between the parts and serves to support the inner ends of the blades 48, 49. The blades are connected to the ends of the bridge 50 by yokes 52 and 53. As shown in Fig. 10, the connection between the yoke, the bridge and the blade

includes a spacer 54, and a plurality of rivets 55. As shown in Fig. 9, the inner ends of the blades 48, 49 are provided with slotted portions 56 which are aligned with apertures 57 in the yoke 52 or 53, and with apertures in the caps 46, 47, to the end that after the parts are assembled, drive screws 58 may be driven through the cap and the casing to secure the yokes in position. Other drive screws 59 are provided for additionally securing the cap to the casing.

Slotted barriers 60 and 61 are carried by the bridge 50. Lagging strips 62 and 63 are secured to the upper surface of the bridge by rivets 64, their outer ends abutting against the barriers and serving to maintain the spacing thereof.

Copper strips 66 and 67 extend between the yokes 52 and 53 and the lagging strips 62 and 63, respectively. The outer ends of the copper strips 66, 67 are gripped between the spacer 54 and the blade, as shown in Fig. 10, and the inner portions pass through a slot in the barrier 60 or 61 and overlie the lagging strips and are soldered thereto, as will hereinafter be pointed out. The portions of the copper strips 66, 67 which are disposed between the yokes and the barriers are notched to provide drop out portions 68.

In this embodiment of my invention, two springs 70 and 71 are provided. These two springs are disposed in side by side relationship.

The spring 70 is anchored to the lagging strip 62, and the spring 71 is anchored to the lagging strip 63. The springs are anchored by means of riveted extrusions 72 which project upwardly from the lagging strips and pass through suitable apertures in the copper strips 66 and 67, and through other suitable apertures in springs 70, 71, respectively, the upper ends of the riveted extrusions being headed over as shown in Fig. 9. The springs are preferably formed from beryllium copper and each spring is provided with a hinge portion 73, which is in the form of a half loop, and which constitutes the stressed portion of the spring. By this arrangement, I am enabled to secure lagging strips 74 to the major portion of the spring. As shown in Fig. 12, the lagging strips 74 and the spring itself are provided with aligned apertures or bores 75 and 76. Molten solder is caused to flow into the bores 75, 76, and it creeps outwardly away from the bores between the contacting surfaces of the lagging strips, and between the surface of the bottom lagging strip and the top surface of the spring 70 or 71, and also between the bottom surface of the spring and the top surface of the copper strips 66 and 67. Thus, all of the parts are maintained in electrical contacting and heat conducting relationship, and the soldered connection between the bottom surface of the spring and the upper surface of the copper strips 66 and 67 serve to maintain the hinge portion 73 of the spring in stressed relationship. The lagging strip 74 and the spring are also secured to each other by a rivet 79, and the lagging strips 62 and 63 are cut away, as indicated by the reference numeral 80, right beneath the rivet so as to assure that there will be no arcing at this point.

In operation, the fuse will blow under short circuit conditions at one or the other of the drop out portions 68. However, under low or moderate overload conditions, the heat generated by the current passing through the copper strips 66 and 67 will cause the bodies of solder 71 and 78 in each of the springs 70 and 71 to be raised in temperature. As the temperature approaches

the melting point of the solder, it will become softened with the result that the bond between the under surface of the springs and the upper surface of the copper strips 66 and 67, will finally give away, causing the springs to be released as shown in Fig. 11. The release of the two springs will be practically simultaneous, for the reason that as soon as one spring is released, the entire electrical load will be thrown on the other spring, the solder of which already is heated to practically the release point. Thus, this additional electrical load will be sufficient to release the second spring, practically simultaneously.

As in the case of the previously described embodiment, the lagging strips 62 and 63 can be dimensioned so as to control the time of blowing. In this embodiment, the blades 48 and 49 also absorb a considerable portion of the heat generated in the copper strips, and of course the lagging strips 74 also absorb the generated heat.

A further modification of the fuse shown in Figs. 3 and 5, is shown in Figs. 13 and 14. Here, the parts are substantially the same and are designated by the same reference numerals, with the exception that instead of two copper strips 24 and 25, a single copper strip 81 is provided. In addition to the drop out portions 34, a central fusing portion 82 is provided which shows a portion of the current passing through the spring 37. Thus, when the solder 39 is raised in temperature to substantially the melting point, and the spring released, an increased electrical load will be thrown on the central fusing portion 82, and this will fuse and open the circuit practically simultaneously. However, the actual opening of the circuit will take place by the fusing of the central fusing portion 82, and the characteristics of such a fusing portion are such that there is a somewhat lesser tendency toward arcing than where the circuit is broken by means of the spring 39. In this embodiment, it will be observed that the positions of the bridge 29 and of the lagging strips 30 and 31 is reversed, in order that the central fusing portion may be spaced from the bridge.

To secure greater uniformity of operation, I have found it desirable to provide a fusible means in the form of a body of metal of substantial heat absorbing capacity. Although in the larger fuse sizes, the heat absorbing capacity of the fusible metal is comparatively small with respect to the heat absorbing capacity of the other elements of the fuse structure, the fact that the stressed portion of the fusible metal is just a part of a larger homogenous body of heat conducting and absorbing material will tend to prevent release of the resilient strip due to localized heating effects at the contacting surfaces. In other words, the fact that release will not occur until all of the fusible metal has been raised to the softening point provides greater uniformity of operation.

The preferred embodiments of my invention shown and described herein are illustrative only, and it is understood that various modifications and changes may be made therein without departing from the spirit of my invention as defined in the following claims.

I claim:

1. A cartridge fuse comprising a substantially cylindrical casing, terminal means at the ends of said casing, a bridge disposed within said casing, means to space said bridge from said casing and providing a substantially rigid mounting

therefor, said bridge being made from electrical insulating material, conducting strips extending between said terminal means and the end portions of said bridge and being provided with fusing portions, a flexurally resilient strip disposed within said casing, means anchoring one end of said resilient strip to said bridge and providing electrical connection with one of said conducting strips, means securing the other one of said conducting strips to another portion of said bridge, and fusible means electrically connecting said last mentioned conducting strip and the free end portion of said resilient strip and maintaining said resilient strip in flexurally stressed condition.

2. A fuse as defined in claim 1 in which the means for securing said last mentioned conducting strip to said bridge comprises an eyelet, and in which the free end of said resilient strip is provided with a bent portion adapted to be received within said eyelet, and in which said fusible means is disposed within said eyelet and surrounds said bent portion.

3. A fuse as defined in claim 2 which is provided with a body of heat absorbing material mounted on said bridge, said eyelet extending through said body of heat absorbing material whereby the temperature of said fusible means will be maintained at substantially the temperature of said body of heat absorbing material.

4. In combination with a fuse as defined in claim 14, a strip of heat absorbing material secured to said resilient strip.

5. A fuse as defined in claim 14 which is provided with a heat absorbing member mounted on said resilient strip, said heat absorbing member and said resilient strip being provided with aligned perforations and said fusible means being disposed in said aligned perforations and contacting said last mentioned conductor means, whereby the temperature of said fusible means will be maintained at substantially the temperature of said heat absorbing member.

6. In a fuse, means providing two parallel circuits, one circuit being maintained in closed position by a comparatively small body of metal which develops a comparatively high degree of heat, and the other circuit being maintained closed by a comparatively large body of metal which is adapted to be ruptured when heated to a moderate extent, the proportions of said bodies of metal being such that under small and moderate overload conditions said second mentioned circuit will open prior to said first mentioned circuit, thereby throwing the entire load on said first mentioned circuit, and causing the same to open, whereby only a comparatively small amount of metal is subjected to volatilization.

7. In a fuse, two superimposed strips arranged in parallel circuit with each other, one of said strips being of limited current carrying capacity, and fusible means to maintain the other in a flexurally stressed condition.

8. In a fuse, two superimposed strips arranged in parallel circuit with each other, one of said strips being of limited carrying capacity, and the other of said strips being of considerably greater current carrying capacity, a body of fusible metal interlocking the end of said second strip to a portion of said first strip to maintain said second strip in a flexurally stressed condition, the arrangement being such that under moderate overload conditions said body of fusible metal will become softened to permit the release of said second strip, thereby throwing

the entire current load on said first mentioned strip.

9. In combination, a fuse link, a first fusing section having a cross section of dimensions such that said fusing section will open under short circuit conditions and a second fusing section having a cross section such that it would ordinarily open prior to said first mentioned fusing section, a resilient current carrying member shunted around said second fusing section, and secured at one end to said fuse link, and a body of fusible material interlocking the other end of said resilient member with an adjacent portion of said link to maintain said resilient member in stressed condition, whereby under small and moderate overload conditions, said body will be elevated to a temperature such that it will permit the release of said resilient member, thereby causing the full load to be thrown on said second fusing section.

10. A cartridge fuse having a bridge, a fuse link spaced from said bridge and secured at either end with respect thereto, and a resilient strip of metal rigidly mounted at one end with respect to said fuse link in substantially superimposed relationship therewith, said resilient strip being formed so that the free end tends to spring away from said fuse link and a body of fusible metal serving to interlock the free end of said resilient strip with said fuse link, whereby said resilient strip is maintained in flexurally stressed condition and in parallel electric circuit with said fuse link.

11. In a fuse having a tubular casing, a fuse link adapted for blowing under short circuit conditions, and circuit opening means operative under moderate overload conditions in series circuit with said fuse link, said latter means comprising a body of fusible metal and a heat absorbing member disposed in thermally conducting relationship with each other and with said fuse link, bridge means for supporting said body of fusible metal, and a flexurally resilient strip secured at one end to said bridge means and having its other end engaged by said body of fusible metal and maintained in flexurally stressed condition thereby, and means supporting said bridge means from said casing including a disk disposed between said fuse link and said circuit opening means, and engaging said bridge means.

12. In a cartridge fuse having a substantially cylindrical casing and terminal means at the ends of said casing, circuit opening means comprising a resilient strip disposed within said casing, supporting means on which said strip is mounted including a bridge element of insulating material, means to space said supporting means from said casing and providing a substantially rigid mounting therefor, means anchoring one end of said resilient strip to said supporting means, the outer end of said resilient strip being biased, in a direction perpendicular to the axis of said cylindrical casing, away from said supporting means, and fusible means engaging the free end portion of said resilient strip and maintaining the same, against said bias, in a flexurally stressed condition, said fusible means being also supported by said supporting means, the anchored end of said resilient strip being electrically connected to one of said terminal means, and said fusible means being electrically connected to the other one of said terminal means.

13. In a cartridge fuse having a substantially

cylindrical casing and terminal means at the ends of said casing, circuit opening means comprising a flexurally resilient strip disposed within said casing, supporting means on which said strip is mounted including a bridge element of insulating material and two heat absorbing elements secured thereto, means to space said supporting means from said casing and providing a substantially rigid mounting therefor, means anchoring one end of said resilient strip to said supporting means, and fusible means engaging the free end portion of said resilient strip and maintaining said resilient strip in flexurally stressed condition, the anchored end of said resilient strip being electrically connected to one of said terminal means, and said fusible means being electrically connected to the other one of said terminal means.

14. A cartridge fuse comprising a substantially cylindrical casing, terminal means at the ends of said casing, a resilient strip disposed within said casing, supporting means on which said strip is mounted including a bridge element of insulating material and two lagging elements secured thereto, means to space said supporting means from said casing and providing a substantially rigid mounting therefor, conductor means extending between said terminal means and the end portions of said supporting means, at least one of said conductor means being fusible under short circuit conditions, means anchoring one end of said resilient strip to said supporting means and providing electrical connection with one of said conductor means, means securing the other one of said conductor means to another portion of said supporting means, and fusible means electrically connecting said last-mentioned conductor means and the free end portion of said resilient strip, and maintaining said resilient strip in flexurally stressed condition.

15. A fuse as claimed in claim 14 in which said conductor means are in the form of strips which overlie the end portions of said supporting means thereby providing two spaced electrically conducting surfaces, and in which said resilient strip includes a coplanar portion adapted to lie against both electrically conducting surfaces, and a looped portion between said coplanar portion and the anchored end of said resilient strip, whereby said looped portion is maintained in flexurally stressed condition by fusible means.

16. A fuse as claimed in claim 15 in which is provided a heat absorbing member mounted on said coplanar portion.

17. A fuse as claimed in claim 14 having a fuse link disposed in parallel circuit arrangement with said resilient strip and said fusible means.

18. A fuse as claimed in claim 15 in which said two conductor means and said fuse link constitute a common element.

GUST A. BERTHEL.
